UNITED STATES PATENT OFFICE.

GORDON L. HENDERY, OF MONTREAL, QUEBEC, CANADA.

DESIGN FOR A BOTTLE.

Application filed November 21, 1927, Serial No. 24,215, and in Canada October 19, 1927. Term of patent 7 years.

To all whom it may concern:

Be it known that I, GORDON L. HENDERY, a subject of the King of Great Britain, of Canada Cement Building, Phillips Square, in the city of Montreal, Province of Quebec, and Dominion of Canada, have invented a new, original, and ornamental Design for a Bottle, of which the following is a specification, reference being had to the accompanying drawing, forming part thereof.

Figure 1 is an elevation of the bottle and Figure 2 is a plan view of the bottom of the bottle, showing my new design.

I claim:

The ornamental design for a bottle, as shown.

In witness whereof, I have hereunto set my hand.

GORDON L. HENDERY.
